C. L. ARNOLD ET AL.

SAW.

FILED JAN. 9, 1922.

UNITED STATES PATENT OFFICE.

CHARLES LESLIE ARNOLD AND CHARLES EDELEN, OF BARDSTOWN, KENTUCKY.

SAW.

Application filed January 9, 1922. Serial No. 527,950.

To all whom it may concern:

Be it known that we, CHARLES L. ARNOLD and CHARLES EDELEN, citizens of the United States, and residents of Bardstown, in the 5 county of Nelson and State of Kentucky, have invented certain new and useful Improvements in Saws, of which the following is a specification.

This invention relates to band saws especially adapted for use by butchers.

An important object of this invention is to provide a band saw having novel means whereby the saw may be tensioned as the occasion requires and whereby the saw may 15 be loosened so that the same may be conveniently disconnected for cleaning or replacement.

A further object is to provide a butcher's saw having novel means whereby the several 20 wheels which support the band saw may be simultaneously operated so that slippage between the saw and the several wheels is reduced to a minimum.

A further object is to provide a saw for 25 use by butchers which is simple to operate, durable in use and cheap to manufacture.

Other objects and advantages of the invention will be apparent during the course of the following description.

30 In the accompanying drawing, forming a part of this application and in which like numerals are employed to designate like parts throughout the same,

Figure 1 is a vertical sectional view 35 through the improved saw.

Figure 2 is a plan view of the improved saw, parts being shown in section.

Figure 3 is a detail section through the saw guiding means.

40 In the drawing wherein for the purpose of illustration is shown a preferred embodiment of the invention the numeral 5 generally designates a frame which is preferably cast in one piece and which is provided

45 at its ends with disk-shaped heads 6 and 7 upon which gear casings 8 and 9 are mounted. The gear case 8 is formed integral with the frame while the gear case 9 is mounted for sliding movement on the disk-shaped 50 head 7. As illustrated in Figure 2 the disk-shaped head 7 is provided with guide flanges 10 which overhang the laterally projecting arms 11 extended from the gear case 9. It will be seen that the laterally projecting 55 arms 11 have a sliding connection with the overhanging flanges 10 so that the gear case

9 may be moved longitudinally on said head. The gear case 9 is provided with a forwardly extending portion 14 having laterally projecting arms 15 overhung by guide flanges 16 extended upwardly from the disk-shaped head 7. The guide flanges 16 cooperate with the guide flanges 10 in holding the gear case 9 against lateral movement or accidental rotation.

60 As illustrated in Figure 1 wheels 19 and 20 are arranged beneath the frame 5 and are secured on the lower end of shafts 120 by means of nuts 21, the said nuts 21 being provided with stems threaded into the lower portion of the shafts 120. Also each nut 21 is provided with a socket for the reception of the hub 22 of the adjacent wheel.

65 The upper end of each shaft 120 is provided with a beveled gear 24 confined within the adjacent gear case and having engagement with a pinion 25. The pinions 25 of which there are two are mounted upon a shaft 26 composed of a pair of sections, one of which is provided with a sleeve 28 having a square bore to receive the squared end 29 of the other section. It is thus seen that the two sections of the shaft 26 are slidably and non-rotatably connected so that the gear case 9 may be moved with respect to 70 the gear case 8 without interfering with the driving connection between the shaft 26 and the wheels 19 and 20. The socketed end of the sleeve 28 is provided with a flange 32 which firmly abuts the bearing 33 extended 75 from the gear case.

80 An electric motor 35 is mounted upon the frame and is connected to the shaft 26 by a train of gears 36 confined within a gear case 37. The electric motor 35 is operated 85 by the current conducted through a line 40, one end of the said line or cord being provided with a plug 41 by means of which the cord may be electrically connected to a socket.

85 Each wheel 19 and 20 is provided with an annular flange 50 about which a band saw 51 is trained. As illustrated in Figure 2, one side of the frame is open so that the saw may be engaged with the material to 100 be cut without interference by the same or the various parts mounted upon the frame. The band saw 51 is passed through a pair of guides 53 carried by the heads 6 and 7. Pairs of upstanding apertured ears 54 are 105 carried by the heads 6 and 7 above the depending guides 53 and pivotally support

grooved guide wheels 55, the grooves in the grooved wheels receiving the upper edge portion of the band saw, whereby to effectively guide the saw. It is thus seen that 5 the saw is effectively guided when engaged with the material so that the possibility of the saw breaking is reduced to a minimum.

The saw or band may be tightened from time to time by means of the adjusting 10 screw 160 extended through a tubular guide 161 and having a threaded terminal portion engaged by a thumb nut 162. A coiled spring 164 is confined within the guide 161 and urges the thumb nut 162 outwardly so 15 that the gear case 9 and consequently the wheel 20 is urged to one end of the frame so that the band saw 51 is at all times maintained taut. As illustrated in Figure 1 the tubular guide 161 is preferably formed 20 integral with the head 7 and when the thumb nut 162 is tightened the tension on the gear case 9 and consequently the wheel 20 is substantially increased. The head 7 is 25 slotted as indicated at 166 to slidably receive the adjacent shaft 120.

In operation, the operator grips the handles 60 and 61 and places one side of the band saw over the material to be cut and lowers the frame so that the saw is moved 30 into engagement with the material. The switch 63 at one end of the handle may be conveniently operated for setting the motor in operation and consequently starting the band saw 51. When it is desired to clean 35 the saw, the tension on the band saw may be released and the saw immediately disengaged from the wheels 19 and 20. The band saw may be adjusted as the occasion requires by the simple adjustment of the 40 thumb nut 162.

As illustrated in Figure 1 the heads 6 and 7 are provided with depending flanges 66 which surround the wheels 19 and 20 and thereby protect the same from engagement 45 with the material being cut or adjacent articles.

Having thus described our invention what we claim is:—

1. A butcher's saw comprising a frame 50 having a pair of spaced disk-shaped heads provided with depending guard flanges, wheels arranged beneath said heads and surrounded by said flanges, shafts connected to said wheels and having gears, gear cases 55 receiving said gears, one of said gear cases being rigidly connected to one of the heads and the other gear case being slidably associated with the other head, an extensible

shaft having pinions engaged with said gears, and a motor connected to said last 60 named shaft.

2. A butcher's saw comprising a frame having a pair of spaced disk-shaped heads provided with depending guard flanges, wheels arranged beneath said heads and surrounded by said flanges, shafts connected to said wheels and having gears, gear cases receiving said gears, one of said gear cases being rigidly connected to one of the heads and the other gear case being slidably associated with the other head, an extensible shaft having pinions engaged with said gears, and a motor connected to said last 70 named shaft, a tubular guide mounted on one of said heads, an adjusting screw extended through said tubular guide and having connection with said slidably supported gear case, and a thumb nut threaded on said adjusting screw.

3. A butcher's saw comprising a frame 80 having a pair of spaced disk-shaped heads provided with depending guard flanges, wheels arranged beneath said heads and surrounded by said flanges, shafts connected to said wheels and having gears, gear cases 85 receiving said gears, one of said gear cases being rigidly connected to one of the heads and the other gear case being slidably associated with the other head, an extensible shaft having pinions engaged with said gears, a motor connected to said last 90 named shaft, a tubular guide mounted on one of said heads, an adjusting screw extended through said tubular guide and having connection with said slidably supported gear case, a thumb nut threaded on said adjusting screw, and a coiled spring confined between one end of said tubular guide and 95 said thumb nut.

4. A portable saw comprising a frame 100 having a pair of heads and a connecting portion, wheels arranged beneath said heads, shafts connected to said wheels and having gears, gear cases mounted on said heads and housing said gears, one of said cases being slidably mounted on the associated head, an extensible shaft rotatably connected to said cases and having pinions in mesh with said first named gears, a motor mounted on the connecting portion of said frame and having connection with said extensible shaft, and means whereby said slidably mounted casing may be moved longitudinally of the frame.

CHARLES LESLIE ARNOLD.
CHARLES EDELEN.
